UNITED STATES PATENT OFFICE.

MARY A. SIMS, OF NEW YORK, N. Y.

DRYING-RAIL AND FOOT-REST FOR HEAT-REGISTERS.

SPECIFICATION forming part of Letters Patent No. 417,102, dated December 10, 1889.

Application filed October 26, 1888. Serial No. 289,212. (No model.)

To all whom it may concern:

Be it known that I, MARY A. SIMS, a citizen of the United States, and a resident of New York, in the county of New York and State 5 of New York, have invented a certain new and useful Improved Combined Drying-Rail and Foot-Rest for Heat-Registers, of which the following is a specification.

My invention relates to improvements in 10 attachments for hot-air registers; and my objects are to provide a simple and easily-adjustable foot-rest and a rail for supporting articles which are to be dried.

My invention consists in the construction 15 and combination of parts, as hereinafter described, and pointed out in the claims.

In the drawings which accompany and form 20 part of this specification, Figure 1 is a perspective view of my device complete, attached to a register; and Figs. 2 to 8, inclusive, are detail views, Fig. 2 being a plan view of the rest, Fig. 3 an end view of the same, Fig. 4 a side view of the rail, Fig. 5 a plan view of the same, and Figs. 6, 7, and 8 being severally 25 enlarged views of the rail hinge.

A represents the frame of a hot-air register to which are secured two clamps B, having pointed rear ends b to facilitate their insertion behind said frame. Secured to and projecting forward from each of the clamps B is 30 a lug C, having two arms terminating in disks c', the inner faces of the disks having several radial grooves c. The ends of a U-shaped rail D fit between the disks c', and are pivoted thereto by means of a pintle d'. Ribs d d, projecting from the sides of the said ends, fit the radial grooves c. The arms of lug C are sufficiently elastic to allow the rail D to be forcibly swung on the pintles d', to cause 35 the ribs d d to engage different grooves c, and be then held in position.

A shelf or foot-rest E is provided with lugs e e to enter openings in the register, and with curved lugs e' e' to engage the cross-bar of rail D, as shown in Fig. 1. When in this position, the parts serve as a foot-rest for warming the feet, or wet shoes or other articles can be placed on the rest to dry or be warmed. By removing the rest E and swinging the rail D to any desired position—as shown, for instance, by dotted lines in Fig. 4—towels or other articles can be placed on said rail for drying or warming.

It will be seen that my device is equally applicable to registers of different sizes and 50 of various patterns of scroll or open work, and there is no outward pull or strain upon the open-work portion of the register.

Having thus described my invention, what I claim, and desire to secure by Letters Patent, 55 is—

1. An attachment for registers, consisting of clamps, bifurcated lugs attached to said clamps and having radial grooves c, and a U-shaped rail having its ends pivoted to said 60 lugs and provided with ribs to fit said radial grooves, substantially as described.

2. In an attachment for registers, the combination of clamps adapted to be connected with the upper part of a register-frame, a U-shaped rail pivotally connected with said clamps, and a shelf or foot-rest having means of connection with the register and the rail, 65 substantially as described.

Signed at New York, in the county of New 70 York and State of New York, this 8th day of October, A. D. 1888.

MARY A. SIMS.
